OIL BURNER CONSTRUCTION

George Irving Carter, Teaneck, N. J.

Application February 25, 1937, Serial No. 127,685

22 Claims. (Cl. 158—76)

This invention relates to oil burner construction.

Particular reference, for descriptive purposes, will be had in this case to that type of oil burner construction in which, for the transformation of the oil into a state in which it is combustible efficiently, a spraying device, such as a nozzle, is used. The invention is directed, among other things, to effecting combustion of the fuel as completely as possible within a very short space, in order that such burner may be capable of utilization in ordinary household furnaces. In many burners in use, the supply of air has been so proportioned that combustion should have proceeded efficiently; yet many factors interfered and prevented efficient results. Combustion may actually be completed; yet it will have been accomplished, if at all, only by introducing a large excess of air with consequent extreme loss of heat.

It is an object of the invention to provide apparatus for burning liquid fuel in which the liquid fuel and the blast air, by the method followed in bringing the blast air to the point where the liquid fuel is atomized, necessarily results in substantially uniform intermixture of fuel and air. Air-streams enter a blast-tube substantially tangentially to the peripheral walls of the tube, the air-streams then gyrating in the tube while moving along a substantially helical path up to the position of the device from which the liquid fuel is being sprayed. This centrifugal flow of the air currents has been found to incorporate the sprayed fuel quickly into the air-streams, producing substantially uniform mixture of air and fuel so that combustion may proceed rapidly.

It is an object of the invention to provide means to control the streams of air entering the tube without interfering with the tangential manner of entry of such streams into the tube.

It is an object of the invention to provide apparatus of the type specified in which the smallest number of elements possible are utilized, wherein the construction may be integrated or resolved into its elements readily, and especially wherein important elements of the apparatus may be separated as a unit from the apparatus, be replaced by a substitute unit, as, for instance, when repair may become necessary, and the unit for repair be taken to some central point for performance of such adjustments or the like as may be necessary, whereupon it may be returned quickly into position, the apparatus all the while being capable of functioning without interruption during such period of repair, and without disturbing the major body of the apparatus.

It is an object of the invention to provide, for apparatus of the type herein set forth, a single power source for making all the parts thereof effective, means made effective by the single

power source producing the separate and distinct air-streams which then act conjointly within the tube in producing the centrifugal action.

It is an object of the invention to mount mechanism of this type in such manner that vibration is substantially absorbed in such manner as to make it unnecessary to cushion the apparatus as a whole. A single shaft, driven by the single power source, may provide, at its ends, the mountings for a plurality of blower fans, the latter being arranged to cooperate individually with ducts leading up to the blast-tube. The power source and the other elements so associated with it are assembled with a platform carried from the frame of the machine in such manner that platform, power source, and these associated elements may vibrate relatively to the body of the machine and yet not produce noise or other undesirable disturbance or situation. Yet this entire assemblage, by removal of but a single coupling, may be separated from the apparatus.

A pair of castings are utilized to define the blower chambers, the blast ducts, and the blast-tube, and, at the same time, to provide a housing or cover for the operating elements of the machine. The apparatus may be constructed so that the removal of but one of such castings discloses, for inspection, all the operating elements of the apparatus; after such disclosure, by the single disconnection mentioned, the elements may be removed from the apparatus.

The structure by which the power source and the blower fans are associated for removal as a unit may also permit the assembly therewith of means for delivering the liquid fuel under pressure to the fuel-spraying device. In the structure herein specifically disclosed, a pump is affixed to and is carried by the platform. The apparatus is arranged so that the pump is driven by the same power source. The pump is thus removable from the apparatus together with the power source. The arrangement is such that the pump is thus also supported so that its vibrations will be absorbed between platform and frame.

The connection between oil pump and spray nozzle tube is shown herein as made by a resilient metallic tube. Such tube, in a construction such as to be described herein, may be coiled in such manner that the tube itself functions as a resilient damping member, functioning to absorb or dampen vibration between platform and frame.

Other objects of this invention will hereinafter be set forth, or will be apparent from the description and the drawings, in which are illustrated certain elements considered pertinent for the demonstration of the invention.

The invention, however, is not intended to be restricted to any particular method of operation, construction, or arrangement of parts,

herein shown and described, or to any particular application of any such apparatus or method, or to any specific manner of use, or to any of various details thereof, herein shown and described, as the same may be modified in various particulars, or be applied in many varied relations, without departing from the spirit and scope of the claimed invention, the elements herein illustrated and described being merely 10 types showing some of various forms the invention might take for practical purposes.

On the drawings in which the same reference characters refer to the same parts throughout, and in which are shown the elements mentioned: 15 Fig. 1 is a plan view of an oil burner embodying features of the invention;

Fig. 2 is an elevational view of the oil burner shown in Fig. 1;

Fig. 3 is a plan view of the oil burner shown in 20 Fig. 1, to an enlarged scale, the cover being removed to disclose the interior construction of the apparatus, the blower fans being broken away in section to clarify the relationship of parts; the motor and the oil pump, and the connecting belt, 25 being shown by dot-and-dash lines;

Fig. 4 is a cross-sectional view substantially as seen from the line 4—4 of Fig. 1, and substantially to the same scale as Fig. 3; the transformer, the motor and the oil pump and the belt connecting them, being shown by dot-and-dash lines; and certain parts being shown in elevation to 30 clarify the disclosure; one of the feet of the mounting, shown in elevation, being associated with a support member shown in cross-section, to 35 illustrate that association;

Fig. 5 is a view in cross-section substantially as seen from the line 5—5 of Fig. 1, and substantially to the same scale as Fig. 3, illustrating the arrangement of the control means for the air flow, 40 the valve controlling the tangential action being shown at fully opened position;

Fig. 6 is a detail cross-sectional view, to an enlarged scale, on the line 6—6 of Fig. 2; and

Fig. 7 is a view of the casing structure, as seen 45 in vertical cross-section from a vertical plane passing through the axis of the motor and fans in Fig. 2, with all parts removed from the apparatus, to illustrate the construction of the casing, the view being one looking from the position of 50 the motor towards the blast tube.

The oil burner, as shown on the drawings, may consist of a frame F, which, in turn, may include a casing 12 carried upon supports 14. Within frame F may be disposed a motor M, which may 55 be of any desired construction, to drive blower fans 16 and 18 of the blowers B, and an oil pump P. The fans are disposed in wells 20 and 22, and discharge into ducts 24 and 26. Associated with the motor is a transformer T for supplying 60 high tension current to electrodes E disposed within blast-tube 28.

Casing 12 may be made up of a pair of castings defining a base 30 and a cover 32. Base and cover are intended to cooperate in a manner 65 hereinafter to be described. The base, which may be a substantially Y-shaped casting, may be shaped to define the bottom sections 34 and 36 of blower wells 20 and 22, from which sections the bottom sections 38 and 40 defining ducts 24 and 70 26 extend forwardly, sections 38 and 40 then converging into the bottom section 42 of control chamber 44 which leads directly into blast-tube 28, sections 34 and 36 and 38 and 40 cooperating 75 to define the arms of the Y, while section 42 and the blast-tube define the leg of the Y.

A lug 46 may extend downwardly from section 42 to define one of supports 14. In lug 46 a vertical channel 48 may be formed to receive a leg 50 fitted to slide vertically within the channel. A slot 52 through the leg and extending substantially vertically may be provided to receive a bolt 54 engaged in lug 46, the head of the bolt, when the bolt is tightened, pressing against leg 50 at the sides of slot 52 to retain leg 50 fixed in position after adjustment.

Leg 46 is thus substantially centrally disposed below the apparatus as a whole. At the rear portions of the inner faces 56 and 58 of wells 20 and 22, vertically extending ribs 60 are formed. Legs 62, with slots 64 similar to slot 52 substantially encompassing these ribs, are capable of sliding vertically relatively to the ribs. Bolts 66, engaged in faces 56 and 58 immediately at the ribs, extend through slots 64, and, in a manner similar to bolt 54, lock legs 62 in position after 20 the legs have been slid to a desired position. Legs 50 and 62 each have footings 68 to provide a foundation for the machine. Thus, the entire assembly is provided a three-point support.

Each of the sections 34 and 36 is substantially 25 identical in construction. Each has an outer wall 70 which is unbroken in its extent. Each inner wall 72 is, however, formed with an opening 74 substantially U-shaped in form to permit air to flow to fans 16 and 18. The fans are set 30 in the wells in the usual manner so that walls 70 of the wells are closely adjacent the fans, while end walls 76 are considerably removed from the fans, in order to insure efficient discharge of air 35 from the fans into ducts 24 and 26 as well as the efficient pick-up of air supplied to the fans to be propelled thereby. Fans 16 and 18, of substantially identical capacity, may be of any desired construction; in the particular case shown, they 40 are of the squirrel-cage type. Shaft 80 of motor M extends completely through the motor, and on the extending ends of the shaft the fans are mounted, thus providing a substantially balanced assembly.

Motor M may have mounting legs 82 by means of 45 which the motor is secured to a platform 84 so that the motor is suspended from the platform, the motor carrying with it, of course, shaft 80 and the fans thereto secured. Platform 84 is provided with a number of feet 86. These feet are tapered downwardly, terminating in pins 81, at the junction of which with the bodies of the feet are defined shoulders resting on complementary shoulders in bores in resilient members 88, which may be cylindrical pieces of resilient rubber. These 50 pieces of rubber may, in turn, be seated in recesses 90 in base 30. For this purpose, base 30 may be provided with a number of bosses 92 in which recesses 90 are formed to open upwardly, these bosses being formed on, and immediately 55 at the top edges of, faces 56 and 58 and of a wall 94 of section 42 formed at the crotch of the Y of casting 30, and extending laterally from the faces and from wall 94 so as to be located entirely within the space 96 enclosed by wells 20 and 22, the associated ducts, and section 42. Thus, these bosses and feet 86, as will appear 60 more fully hereinafter, are beyond the extent of any portion of cover 32 so that the cover may easily be slipped into position. The tapered ends 65 of feet 86, extending into the bores of members 88, tend to distend the members so that they resiliently engage the walls of recesses 90.

A bracket 98 has a footing engaged against the bottom face of platform 84, the bracket pro- 70 75

viding a pair of lugs 100 for engagement against a face 102 of oil pump P, whereby the oil pump may be retained rigidly with relation to the platform. Any suitable type of oil pump structure 5 may be utilized for the purposes of this invention. In the particular case shown, the pump, one of small extent, as, for instance, of the gear type, has a shaft 104 extending laterally therefrom. On this shaft is a pulley 106 over which is 10 trained a belt 108 to be engaged over a pulley 110 secured on shaft 80. In this manner, motor M simultaneously drives the oil pump while the entire assembly is mounted on platform 84 which in turn is cushioned through members 88 to absorb any vibration produced as blowers and oil 15 pump operate.

In the case shown, an oil-filtering chamber 112 is substantially integrally formed with the oil pump. From chamber 112 leads piping 114, 20 connected in turn to spray tube 116. On wall 94 may be an extending ledge 118 formed with a semi-cylindrical recess 120 in which one end 122 of tube 116 may be supported. A clamp piece 124 having a complementary recess 126 is positioned over end 122 seated in recess 120, and is held secured in position by suitable devices 128, such as cap screws or the like, thus retaining the tube in position. Suitable means such as a coupling 130 serves to connect piping 114 with 25 tube 116. Piping 114 may be of resilient copper or similar metal, and may be bent into a loop 132 in such manner that it will form a resilient connection between the frame and the oil pump. Such a connection would function 30 to dampen vibrations, with relation to the casting, of elements mounted upon the platform.

Tube 116 extends beyond wall 94 to pass through a spider 134 positioned within blast-tube 28, the radiating legs 136 of which are of such 40 length as to contact with the walls of the blast-tube and thus provide a support for tube 116 and electrodes E which also are carried in the spider. The spider may be secured on tube 116, as, for instance, by a set-screw, to retain the assembly 45 in position. Suitable passages 138 are formed in the legs of the spider for insertion of the electrodes, the legs being slit up to the passages, and any suitable compressing means being utilized, in order to clamp the electrodes in position and against separation from the spider which provides the only fixed support for the electrodes. Beyond the spider, a nozzle 142 is 50 affixed to tube 116, the electrode points 144 being positioned immediately at this nozzle.

Carried on top of platform 84 may be transformer T which may be secured to the platform in any desired manner. Leads 146 are connected to terminals of the transformer and pass downwardly through a cut-away section 148 of the platform, and then through insulating nipples 150 mounted in wall 94 to be coupled to the electrodes. The nipples are seated in notches 152 formed in the wall.

Cover 32 may be retained in position on the base by suitable securing devices 154, such as cap screws, extended through openings 156 at bosses 158 provided for that purpose in the cover, to engage within tapped openings 160 in similar bosses 162 in the base. Cover 32 can be 55 considered to be divided into three distinct portions. Looking at the cover as if it were inverted, it will be found that there is a large well 164 which coincides with space 96 and within which the upward extension of the platform and the transformer is housed. As a matter of fact, when the

cover is in position, substantially all the operating parts of the apparatus are guarded and substantially housed. Furthermore, there are the top sections 166 and 168 to coincide with sections 34 and 36 in defining blower wells 20 and 22, and top sections 170 and 172 to cooperate with sections 38 and 40 in defining ducts 24 and 26. For the production of these different sections, wall 174, which defines well 164, seats immediately over the top edges of walls 72 and over 10 wall 94 when the cover is in position. Wall 174 does not, however, interfere with bosses 92 nor with the cooperation with said bosses of feet 86 as the wall is no thicker than the normal thickness of walls 72. Notches 152 are closed by a 15 section 176 of wall 174 complementary to the formation of the electrodes; section 176 also has a cut-out 178 likewise complementary to clamp piece 124.

Walls 180 and 182, which define the outer 20 bounds of the cover, are formed to coincide with the outer walls of the base. It will be noted that cover 32 does not extend the entire length of blast-tube 28 which is made substantially integral with the base, but terminates in a section 184, complementary to section 42, and section 184 terminates in a bell 186. The bell rests upon the inner edge of the blast-tube, thus producing a substantially sealed tube.

Ducts 24 and 26, defined by sections 38 and 40, 30 and the complementary sections 170 and 172 of cover 32, are substantially parallel to each other, and are substantially at the same level. However, in the delivery ducts 188 and 190 providing communication between ducts 24 and 26 35 and control chamber 44, a different construction is involved. Duct 188 is directed upwardly to meet control chamber 44 tangentially at its uppermost portion, while duct 190, on the other hand, is directed downwardly to meet control 40 chamber 44 tangentially at its lowermost portion so that its air-stream will enter the chamber substantially at its lowermost portion, and diametrically opposite the position of entry of the stream from duct 188. Considering a section of 45 the apparatus such as shown in Fig. 5, which is transversely across the chamber and the associated apparatus at this intersection, the construction will be found to define a pair of ports 192 and 194 opening between the respective ducts 50 188 and 190 and the chamber. The incline of the respective ducts to the respective ports is such that the respective air-streams enter the blast-tube substantially tangentially. Both ducts are directed forwardly at a slight angle so that, 55 despite the fact that the streams enter the chamber going substantially in opposite directions, yet, by reason of the fact that the points of entry are at substantially oppositely disposed diametrical positions, and by reason of the slight forward inclination of the ducts, a helical flow of both air-streams within the blast-tube will result.

In chamber 44 is disposed a cylindrical shell 196, a section of which is completely broken away to provide an opening 198, while, at the oppositely disposed portion of the shell, another opening 200 of the same character is formed, except that a rib 202 connects the two plates 204 and 206 of the shell thus defined, so that the plates may rotate together and simultaneously. Plates 204 and 206, in their movement, control the opening of ports 192 and 194, and thus provide means for controlling the flow of air from the blower fans into the blast tube. However, it 75

will be noted that the opening edges 208 of the plates move towards and away from the extreme top wall and extreme bottom walls of ducts 188 and 190, respectively, so that the air-flow to chamber 44 will, at all times, be restricted to the outermost portions of the ducts and chamber, so that the tangential action of these air-streams will not be affected, the only effect being in more finely defining the extent of these air-streams as they enter the chamber, and the blast-tube which lies immediately adjacent. A bolt 210 may be engaged with rib 202, and be extended through a slot 212 in wall 214 of the chamber, thus providing means for manipulating the valve defined by shell 196 from a position externally of the blast-tube. By tightening the bolt into engagement with wall 214, it provides means for fixing the valve in position, once it has been adjusted.

In the substantially parallel sections of ducts 24 and 26, dampers 216 may be provided. These dampers may be in the form of circular plates 218, held substantially in the same plane, but at opposite ends of a single rod 220 so that they are simultaneously movable and to the same degree. This rod may be located in notches 222 in walls 72 which cooperate with similar notches in wall 174, so that the rod is locked in position by the assembly of the cover with the base. These dampers may be used to control the quantity of air flowing to ports 192 and 194 without varying the fineness of the stream entering the chamber. A crank arm 228 may be affixed to rod 220 and be pivotally connected to a link 230. The link may have a slot 232 in the body thereof through which may extend a bolt 234 to engage in one of faces 56 or 58 to be used as means for locking the dampers in an adjusted position.

The air-streams, entering the blast-tube, by the position of their entry, will swirl through the blast-tube. The slight forward propulsion of the streams entering chamber 44, in addition to the pressures attained, serve to cause the streams to move forwardly towards the nozzle. Since, from this swirling action, to a degree at least, the moving gases will tend to move out close to the outer walls of the fire-tube, a mouthpiece ring 236 may be assembled at the extreme end of the blast-tube in order more positively to converge the gases once they have picked up the liquid fuel. This mouthpiece may have a converging inner wall 238 coming up to an outlet opening 240 smaller than the bore of the blast-tube. The continuously swirling gases will thus be brought more closely into intermixing relationship with the fuel as they pass beyond that point because of this close relationship between gases and fuel to be consumed. The ring may be held in position by means of set-screws 242, extended through the walls of the blast-tube adjacent the end, and engaged in a groove 244 in a flange 246 of the ring.

After screws 154 have been removed, the cover may be separated from the base at will merely by disconnecting coupling 130, and thus releasing the connection between the oil pump and tube 116, the platform together with its assembled elements may be lifted out of position. Of course, rod 220 may be disconnected from the apparatus by releasing its bolt 234 to permit this separation. Once the separation has been effected, a similar and identical unit may be placed in position, and by these simple connections, made to function in place of the other unit, which may then be

removed to a central factory for such repairs as may be found necessary.

Many other changes could be effected in the particular elements designed, and in the methods of operation and use, and in the apparatus herein set forth, and in specific details thereof, without substantially departing from the invention intended to be defined in the claims, the description being merely of elements illustrating certain phases of the spirit of the invention.

What is claimed as new and useful is:—

1. In oil burner construction, a plurality of air-blast ducts, a single blast-tube, the blast-tube at one end thereof having a plurality of ports opening therethrough, each of the ducts discharging into the blast-tube through one of the ports, the direction of the air-blasts from the several ducts entering the blast-tube through the several ports producing a single cyclonic air-flow the blast-tube, and means for simultaneously controlling the effective opening of all the ports.

2. In oil burner construction, a plurality of air-blast ducts, a single blast-tube, the blast-tube at one end thereof having a plurality of ports opening therethrough, each of the ducts discharging into the blast-tube through one of the ports, the direction of the air-blasts from the several ducts entering the blast-tube through the several ports producing a single cyclonic air-flow through the blast-tube, and means mounted for rotation in the blast-tube to control simultaneously the effective opening of all the ports.

3. In oil burner construction, a pair of air-blast ducts extending in substantially the same general direction, a single blast-tube between and extending in substantially the same general direction as the ducts, an oil-diffusing device within the blast-tube and disposed substantially axially thereof, the blast-tube at one end thereof having substantially diametrically opposed ports opening therethrough, each of the ducts being provided with an end to connect the duct to a port, means for simultaneously impelling air through the ducts substantially in the same general direction, the end of each duct being directed obliquely forward in the same general direction as its duct, the direction of the air-blasts from the ducts entering the blast-tube through the several ports being effective to cause the air within the blast-tube to move up to the oil-diffusing device as a single cyclonic air-flow moving in substantially the same general direction through the blast-tube, and means for controlling the effective opening of the ports.

4. In oil burner construction, a plurality of air-blast ducts, a single blast-tube, the blast-tube at one end thereof having a plurality of ports opening therethrough, each of the ducts discharging into the blast-tube through one of the ports, means for simultaneously impelling air through the ducts substantially in the same general direction, the direction of the air-blasts from the several ducts entering the blast-tube through the several ports producing a single cyclonic air-flow through the blast-tube, means for controlling the effective opening of the ports, and means for simultaneously controlling the flow of air through all the ducts independently of the port-controlling means.

5. In oil burner construction, a pair of air-blast ducts extending in substantially the same general direction, a single blast-tube between and extending in substantially the same general direction as the ducts, the blast-tube at one end thereof having a plurality of ports opening therethrough,

each of the ducts discharging into the blast-tube through one of the ports, means for simultaneously impelling air through the ducts substantially in the same general direction, the direction of the air-blasts from the ducts entering the blast-tube through the several ports producing a single cyclonic air-flow through the blast-tube, means for controlling the effective opening of the ports, a rod extending transversely of and into both ducts, a plate on the rod in each of the ducts for simultaneously controlling the flow of air through the ducts, and means for rotating the rod.

6. In oil burner construction, a Y-shaped frame, the leg of the Y being defined by a blast-tube, the arms of the Y being defined by a pair of blower casings and blast ducts leading away from the blower casings to the blast-tube; a carrier resiliently supported upon and between the ducts; a motor suspended from the carrier, the shaft of the motor extending in opposite directions from the motor and into both casings; and a blower on the shaft in each of the casings.

7. In oil burner construction, a frame including a blast-tube, a pair of legs extending substantially parallelly away from the blast-tube and spaced from each other to provide an opening behind the blast-tube, the legs being substantially open sections, each leg being provided with a communicating open section to provide a connection to the blast-tube, and a single cover for the frame and for the opening to form blast ducts with the open sections.

8. In oil burner construction, a frame including a blast-tube, a pair of legs extending substantially parallelly away from the blast-tube and spaced from each other to provide an opening behind the blast-tube, the legs being substantially open sections, each leg being provided at one end with a communicating open section to provide a connection to the blast tube, blower wells at the other ends of the leg open sections, a single cover for the frame and for the opening to form blast ducts with the open sections and blower casings with the blower wells, a shaft extending into both casings, a blower on the shaft in each of the casings, a motor carried in the opening for driving the shaft, and support means for the frame, the support means comprising three members, two of the members being positioned individually in association with the casings, and one of the members being positioned beneath the blast-tube, each of the members being individually adjustable to regulate its own height.

9. In oil burner construction, a frame including a blast-tube, a pair of legs extending substantially parallelly away from the blast-tube and spaced from each other to provide an opening behind the blast-tube, the legs being substantially open sections, each leg being provided at one end with a communicating open section to provide a connection to the blast-tube, blower wells at the other ends of the leg open sections, a single cover for the frame and for the opening to form blast ducts with the open sections and blower casings with the blower wells, a carrier resiliently supported upon the frame and in the opening between the legs, a motor supported by the carrier, the shaft of the motor extending in opposite directions from the motor and into both casings, a blower on the shaft in each of the casings, and support means for the frame, the support means comprising three members, two of the members being positioned individually in association

with the casings, and one of the members being positioned beneath the blast-tube, each of the members being individually adjustable to regulate its own height.

10. In oil burner construction, a frame including a blast-tube, and a pair of legs extending substantially parallelly away from the blast-tube and spaced from each other to provide an opening behind the blast-tube; the legs being substantially open sections, the legs having a common junction point at one end with the blast-tube, blower walls at the other ends of the leg open sections; a single cover for the frame, for the junction point, and for the opening to form blast ducts with the open sections and blower casings with the blower wells; the blast-tube at diametrically opposed portions thereof at the junction point having ports to provide individual communication for each blast duct with the blast-tube; a single valve at the junction point for determining the degree of opening of the ports; an oil-diffusing device in the blast-tube; electrodes in the blast-tube; a carrier resiliently supported upon and in the opening, a transformer for the electrodes mounted on the carrier; a motor and an oil-pump suspended from the carrier, the shaft of the motor extending in opposite directions from the motor and into both casings; means on the shaft for driving the oil-pump; a blower on the shaft in each of the casings; and support means for the frame, the support means comprising three members, two of the members being positioned individually in association with the casings, and one of the members being positioned beneath the blast-tube, each of the members being individually adjustable to regulate its own height.

11. In oil burner construction, a plurality of air-blast ducts, a single blast-tube having a plurality of ports opening through the walls of the blast-tube at one end thereof, each duct being connected to the blast-tube through one of the ports and being positioned to direct its blast through the port tangentially of the blast-tube, the direction of the air-blasts from the several ducts entering the blast-tube through the several ports producing a single cyclonic air flow through the blast-tube, and means for controlling the effective opening of the ports while maintaining the tangential direction of the blasts.

12. In oil burner construction, a plurality of air-blast ducts, a single blast-tube having a plurality of ports opening through the walls of the blast-tube at one end thereof, each duct being connected to the blast-tube through one of the ports and being positioned to direct its blast through the port tangentially of the blast-tube, the direction of the air-blasts from the several ducts entering the blast-tube through the several ports producing a single cyclonic air flow through the blast-tube, and a single valve for simultaneously controlling the effective opening of all the ports while maintaining the tangential direction of the blasts.

13. In oil burner construction, a plurality of air-blast ducts, a single blast-tube having a plurality of ports opening through the walls of the blast-tube at one end thereof, each duct being connected to the blast-tube through one of the ports and being positioned to direct its blast through the port tangentially of the blast-tube, the direction of the air-blasts from the several ducts entering the blast-tube through the several ports producing a single cyclonic air flow through the blast-tube, and a sleeve mounted for

rotation substantially coaxially in the blast-tube, the sleeve having ports for registry with the blast-tube ports to control the effective air delivery of the blasts while maintaining the tangential direction of the blasts.

14. In oil burner construction, a pair of air-blast ducts extending in substantially the same general direction, a single blast-tube between and extending in substantially that same general direction, an oil-diffusing device within the blast-tube and disposed substantially axially thereof, the walls of the blast-tube at substantially diametrically opposed positions at one end thereof having ports opening therethrough, each duct being provided with an end to connect the duct to the port, means for impelling air simultaneously and substantially at the same rate through the ducts substantially in that same general direction, the duct end being directed obliquely forward in that same general direction so that air-blasts from the ducts entering the blast-tube through the several ports cause the air within the blast-tube to move up to the oil-diffusing device as a single cyclonic air-flow moving in substantially that same general direction through the blast-tube, and means for controlling the effective air delivery through the ports.

15. In oil burner construction, a Y-shaped frame, the leg of the Y being defined by a blast-tube; the arms of the Y being defined by a pair of blower casings and blast ducts leading away from the blower casings to the blast-tube, the ducts and the casings being positioned in spaced apart relationship; the walls of the casings being substantially unbroken except for air inlets in directly opposed walls of the casings opening into the space between the casings; a motor mounted within the space between the casings, the shaft of the motor extending out of the space in opposite directions from the motor and into both casings through the air inlets, and a blower on the shaft in each of the casings.

16. In oil burner construction, a frame including a blast-tube, a pair of legs extending substantially parallelly away from the blast-tube and spaced from each other to provide an opening behind the blast-tube, each leg being substantially an open section of a tube, each leg being provided at one end with an open section connecting the leg to the blast-tube, blower wells at the other ends of the leg open sections, opposed walls of the wells having air inlets opening therethrough, and a single cover extending over both legs and the wells to form blast ducts with the open sections of the tubes, and to form with the blower wells blower casings having air inlets opening into the space between the blower wells.

17. In oil burner construction, a plurality of air-blast ducts, a single blast-tube, and communicating means between the ducts and the blast-tube for directing the several blasts from the ducts angularly forwardly away from the point of entry and also tangentially of the blast-tube at the point of entry into the blast-tube to unite within the blast-tube to produce a single air flow moving through the blast-tube away from the entry end but gyrating cyclonically about the axis of the blast-tube.

18. In oil burner construction, a plurality of air-blast ducts, a single blast-tube, and communicating means between the ducts and the

blast-tube at equal radial angular intervals around the axis of the blast-tube for directing the several blasts from the ducts angularly forwardly away from the point of entry and also tangentially of the blast-tube at the point of entry into the blast-tube to enter the blast-tube at equal radial angular intervals and unite within the blast-tube to produce a single air flow moving through the blast-tube away from the entry end but gyrating cyclonically about the axis of the blast-tube.

19. In oil burner construction, a Y-shaped frame, the leg of the Y being defined by a blast-tube; the arms of the Y being defined by a pair of blower casings and blast ducts leading away from the blower casings to the blast-tube, the ducts being positioned in spaced apart relationship; a carrier in the space between the ducts and removably supported upon the ducts, a motor supported by the carrier and within the space, the shaft of the motor extending out of the space in opposite directions from the motor and into both casings, and a blower on the shaft in each of the casings.

20. In oil burner construction, a plurality of substantially parallel air-blast ducts, a single blast-tube, individual means cooperating with each duct for impelling air simultaneously and substantially in the same general direction through the several ducts, and means for guiding the air-blasts from the several ducts into the blast-tube substantially tangentially of the blast-tube and in a direction having a substantial directional component of said general direction, the guiding means being positioned relatively to the blast-tube so that the air-blasts unite in the blast-tube into a single cyclonic air-flow moving through the blast-tube in substantially that same general direction.

21. In oil burner construction, a plurality of substantially parallel air-blast ducts, a single blast-tube between and substantially parallel to the ducts, the blast-tube having a plurality of ports opening therethrough adjacent one end thereof, individual means in each duct for impelling air substantially in the same general direction simultaneously through the several ducts, and each of the ducts being provided with an end bent angularly forwardly and connected to a port to direct its air-blast from its duct substantially tangentially into the blast-tube through the port with a substantial directional component of said general direction but as an element of a single cyclonic air-flow moving in substantially that same general direction through the blast-tube.

22. In oil burner construction, a plurality of air-blast ducts, a single blast-tube, a blower for each duct, means for driving the blowers synchronously to produce equally effective blasts in each duct, and means connecting the ducts to the blast-tube to direct the air-blasts from the several ducts in non-interfering relation to each other and substantially tangentially of the blast-tube and, on entry into the blast-tube, with a substantial component of motion in the direction of movement of the air-blasts along the tube from the point of entrance to the outlet mouth of the tube to cause the several blasts to gyrate continuously within the blast-tube.
